UNITED STATES PATENT OFFICE.

ALONZO W. WAGONER, OF HAMMONVILLE, KENTUCKY.

FOLDING CRATE.

Application filed May 20, 1927. Serial No. 192,950

This invention relates to improvements in folding crates, and has more particular reference to that type of crate commonly employed for shipping fowl or the like.

5 The primary object of the invention is to provide an improved folding crate of the above kind which is simple and durable in construction and capable of being readily unfolded and set up for use, or folded or collapsed for return to the shipper.

10 A more specific object is to provide a folding crate of that type embodying a bottom wall and inwardly folding side and end walls hinged to the bottom wall for swinging upon horizontal axes, a removable top wall, and simple and efficient means for retaining the side and end walls in unfolded positions with the top wall effectively held in place.

15 A more specific object is to provide a folding crate of the above kind in which the walls will be firmly held in proper relation when the crate is unfolded and set up for use, thereby preventing any material relative movement of the walls and minimizing liability of weakening or damaging the crate 20 from repeated re-use.

25 A still further object is to provide simple and efficient means for attaching the side and end walls to the bottom wall and mounting them for the required vertical swinging movement upon horizontal axes.

30 Other objects will be come apparent as the nature of the invention is better understood, and the same consists in the novel form, combination and arrangement of parts herein- 35 after more fully described, shown in the accompanying drawings and claimed.

35 In the drawings, wherein like reference characters indicate corresponding parts throughout the several views,

40 Figure 1 is a side elevational view of a folding crate constructed in accordance with the present invention, and in unfolded condition as set up for use;

45 Figure 2 is a horizontal section taken upon line 2—2 of Figure 1;

50 Figure 3 is a transverse section on line 3—3 of Figure 1;

55 Figure 4 is a side elevational view of the 50 crate collapsed;

Figure 5 is an end view of the crate collapsed;

Figure 6 is a section on line 6—6 of Figure 4;

55 Figure 7 is a top plan view of the crate in its set up condition as shown in Figure 1;

Figure 8 is an enlarged fragmentary vertical section on line 8—8 of Figure 1; and

Figure 9 is a fragmentary vertical section 60 on line 9—9 of Figure 8.

Referring more in detail to the drawings, the bottom wall of the crate preferably comprises a rectangular rigid frame 5 nailed or otherwise permanently secured upon the margin of a rectangular bottom panel preferably 65 composed of a plurality of thin transverse boards 6 arranged in edge to edge contiguous relation as indicated in Figures 2 and 3. The side and end walls of the crate are substantially of the same general construction, and each includes a rectangular frame of proper 70 size and embodying top and bottom rails 7 and 8, respectively, rigidly connected at their ends by end rails 9, and at intervals between the end rails by upright cylindrical rods or rungs 10.

75 The top and end rails of the frame of the side and end walls are preferably of rectangular cross-section, while the lower rails 8 thereof are of cylindrical form and journaled in pairs of alined cylindrical bearing sleeves 11, whereby the side and end walls may be 80 swung inwardly and downwardly to horizontal folded position, or upwardly and outwardly to vertical position as respectively indicated best in Figures 3 and 6.

85 Disposed in spaced parallel relation to and above the end rails of the bottom frame 5, are 90 supporting bars 12 which are rigidly fastened to said end rails of the frame 5 by means of bolts 13 passing through these parts, suitable spacing sleeves 14 being placed upon the bolts 13 between the supporting bars 12 and the end rails of the bottom frame 5 for maintaining the supporting bars 12 in the proper 95 spaced relation to the end rails of the frame 5 as shown. The bearing sleeves 11 are provided with rigid depending bolts or threaded stems 15, and these bolt stems of the bearing sleeves 11 for the side walls extend downwardly through the side rails of the bottom frame 5 and are firmly held thereto by nuts applied to said stems, as shown. In a like manner, the bearing sleeves 11 for the end walls have their threaded bolt stems passed 100 through the supporting bars 12 and secured therein by means of nuts applied to the stems of said bearing sleeves. In this way, ventilation is allowed between the bottom wall and the supporting bars 12, while the bearing sleeves 11 for the end walls are mounted at a 105 higher elevation than those for the side walls. Thus, the side walls may be swung inwardly 110

onto the bottom in substantially horizontal positions as shown in Figure 6, whereupon the end walls may be similarly folded inwardly onto the end portions of the side walls 5 to also assume horizontal positions in a manner which is generally well known in the art.

It will be noted that the side walls are of such length that the end rails 9 thereof will flatly abut the adjacent inner sides of the end rails of the end walls when said side and end walls are in vertical operative position as shown in Figure 2, and means is provided to clamp each end rail 9 of the frames of the end walls to the adjacent end rail 9 of the frames of the side walls, whereby the several walls will be firmly held against relative movement and prevented from swinging inwardly to folded or collapsed position. As shown, each clamping means consists of a 20 plate 16 pivoted as at 17 to the inner side of the associated end rail 9 of the end wall frame and positionable to extend inwardly in engagement with the adjacent inner side of the adjacent end rail 9 of the adjacent 25 side wall so as to hold the latter against swinging inwardly to folded position, a keeper loop 18 being hinged to the inner free end of the plate 16 for being swung outwardly against the adjacent inner side of 30 said end rail 9 of the side wall for reception of and frictional engagement with a projecting end tongue 19 upon the free end of a hinged hasp 20 pivoted upon the outer side of the adjacent end rail 9 of the end wall and 35 positionable to extend inwardly across the outer face of the adjacent end rail 9 of the side wall as shown in Figure 2. A lateral outwardly projecting keeper pin 21 is provided on the said end rail of the side wall for engagement by the keeper 20 when it is positioned to have its tongue 19 engaged by the keeper loop 18. In this way, the adjacent ends of the side and end walls are firmly held together when in set up or vertical position, although dis-connection of the same may be 40 readily effected by simply swinging the keeper loop 18 inwardly out of engagement with the extension 19 and then swinging the hasp 20 upwardly out of engagement with the keeper pin 21. It will be noted that the plate 45 16 is pivoted to the end rail 9 of the associated end wall to swing in a plane parallel with the latter so that said plate and the keeper loop 18 carried thereby may be swung 50 downwardly alongside said end rail of the end wall and out of the path of the side wall for permitting the latter to be swung inwardly to collapsed position.

It will be noted that when the side and end walls are operatively disposed in a vertical position, the top rails 7 of the end walls will be located above the top rails of the side walls as shown in Figure 1. It will be further noted that the top rails 7 of the end walls 55 are reduced in thickness at their inner sides

to expose inner portions of the upper ends of the end rails 9 of the end walls as indicated at 22. A top wall is provided including a rectangular frame 23 arranged to seat upon the upper edges of the top rails 7 of the side walls and upon the exposed upper end portions 22 of the end rails of the end walls when the side and end walls are vertically disposed as shown in Figure 1. The end rails of the top wall frame 23 are provided with 60 sockets 23^a which open through the outer sides thereof and are adapted for removable reception of inwardly projecting dowel pins 24 rigid with and projecting inwardly from the top rails 7 of the end walls, whereby the top wall is effectively retained in place when the end walls are clamped against the ends thereof and against the ends of the side walls as described above.

In folding the crate, the keeper loops 18 are swung inwardly out of engagement with the tongues 19 of the hasps 20, and then the plates 16 are swung downwardly out of the way to permit the side walls to be folded inwardly and downwardly to the horizontal position of Figure 6. The hasps 20 are then swung upwardly and outwardly, and disengaged from the keeper pins 21, whereupon the end walls are swung outwardly a slight distance to disengage the dowel pins 24 from the end sockets of the top wall frame 23. This permits the side walls to be freely swung to the horizontal position and also permits removal of the top wall. The end walls are then swung inwardly and downwardly to horizontal positions upon the side walls which have been previously swung inwardly to the horizontal position of Figure 6, and then the top wall is placed upon the end walls as shown in Figure 4. Lateral headed keeper pins 25 are provided at proper points on the side rails of the top wall frame 23 for being engaged by the hasps 20 of the end walls when the device is collapsed and the top wall is positioned upon the end walls as mentioned above, whereby the top wall is effectively held to the collapsed body with the latter retained in its collapsed position, as shown in Figure 4.

In view of the above, it will be seen that the crate may be folded into compact form and readily retained in such condition without the use of additional fastening means, although just as effectively. In unfolding the crate and setting it up in condition for use, the hasps 20 are disengaged from the keeper pins 25 and the top wall is then removed. The end walls are then swung upwardly and outwardly past a vertical position and the side walls are thereafter swung upwardly and outwardly to vertical position. The top wall is then placed upon the upper edge of the side walls and the end walls are brought together so as to cause dowel pins 24 to enter the sockets in the end rails of the top wall frame 23. The clamping devices at the corners of the crate are then

operatively disposed with the keeper loops 18 engaging the tongues 19 of the hasps 20 as shown in Figures 1 and 2 and explained above, whereupon the end walls are held against separation for maintaining the top wall in place upon the side walls, and the side walls are effectively held against swinging inwardly to collapsed position. The walls are then so connected and braced as to prevent any perceptible relative movements therebetween and to thereby guard against weakening or damaging of the structure due to the rough usage to which devices of this kind are put during transit.

15 The top wall is of generally well known construction including a pair of spaced parallel longitudinal intermediate rails 26 and transverse cylindrical bars or rungs 27 rigidly connecting the side rails of the top frame 23 and extending through the intermediate rails 26. Certain of the rungs 27 have their intermediate portions removed between the intermediate frame bars 26 to provide an opening through which the chickens or the like may be placed into or removed from the crate, and arranged to close this opening is a hinged closure consisting of a pair of spaced parallel bars 28 rigidly connected at intervals by spaced parallel rungs 29, corresponding ends of the bars 28 being hinged upon the intermediate portion of the rung 27 at one end of the opening, and the other ends of the bars 28 being adapted to rest upon the intermediate portion of the rung 27 at the other end of the opening. The closure is slightly narrower than the space between the intermediate bars or rails 26 of the top frame, and it is urged laterally toward one of the rails 26 by means of a helical compression spring 30 encircling the rung upon which the closure is hinged between one of the intermediate rails 26 and the adjacent bar 28 of the closure. Rigidly carried by the other bar 28 of the closure near the free end of the latter is an angular latch plate 31 having a lateral outwardly projecting end adapted to engage beneath the other adjacent bar 26 when the closure is in its closed position and urged laterally by the spring 30. By shifting the closure bodily against the action of the spring 30, the catch plate 31 will be disengaged from beneath the associated rail 26 so that said closure may be swung upwardly to open position. The closure is swung downwardly to partly closed position and then shifted laterally against the action of the spring 30 so as to remove the projecting end of the catch plate 31 from the path of the adjacent rail 26 and permit full closing movement of the closure. By then releasing the closure the spring 30 will shift it laterally to engage the projecting end of the latch plate 31 beneath the adjacent rail 26, whereupon the closure is effectively retained in closed position.

The ends of the top and bottom rails 7 and 8 are preferably bolted together by means of bolts 32 extending through the end rails 9 so as to provide a strong construction.

From the foregoing description it will be seen that I have provided a very simple and durable form of knock-down folding shipping crate especially suitable for the shipping of chickens and the like. It will further be seen that the construction may be manufactured so as to be of extremely light weight without sacrificing durability. Still further, the various walls are firmly held together in proper relation and assembled condition when the crate is unfolded and set up for use, so that accidental collapsing or material relative movement between the walls is absolutely prevented without the use of expensive or complicated fastening devices.

Minor changes may be made without departing from the spirit and scope of the invention as claimed.

What I claim as new is:—

1. In a folding crate, a bottom wall, end and side walls respectively hinged to the bottom wall upon horizontal pivots disposed in different horizontal planes, said end and side walls embodying rectangular frames having end rails, and means to snugly embrace adjacent end rails at the corners of the crate to releasably clamp the same together and hold the end and side walls in unfolded vertical position, each of said end rail clamping means embodying a plate and a hasp pivoted on opposite sides of an end rail of one wall and a swinging keeper loop engageable across the inner side of the adjacent end rail of the adjacent wall and hinged to the pivoted plate, said hasp having an extension tongue releasably engageable by said keeper loop.

2. In a folding crate, a bottom wall, end and side walls respectively hinged to the bottom wall upon horizontal pivots disposed in different horizontal planes, said end and side walls embodying rectangular frames having end rails, means to snugly embrace adjacent end rails at the corners of the crate to releasably clamp the same together and hold the end and side walls in unfolded vertical position, each of said end rail clamping means embodying a plate and a hasp pivoted on opposite sides of an end rail of one wall and a swinging keeper loop engageable across the inner side of the adjacent end rail of the adjacent wall and hinged to the pivoted plate, said hasp having an extension tongue releasably engageable by said keeper loop, a separate top wall, and keeper pins selectively engageable by the hasps for respectively connecting adjacent end rails when the crate is set up and connecting the top wall to the end walls when the crate is collapsed.

In testimony whereof I affix my signature
ALONZO W. WAGONER.
